D. A. Goodrich,

UNITED STATES PATENT OFFICE.

DAVID A. GOODRICH, OF NORTH PLATTE, NEBRASKA.

FENCE STRUCTURE.

1,012,626.

Specification of Letters Patent. Patented Dec. 26, 1911.

Application filed January 19, 1911. Serial No. 603,505.

To all whom it may concern:

Be it known that I, DAVID A. GOODRICH, a citizen of the United States, residing at North Platte, in the county of Lincoln and State of Nebraska, have invented certain new and useful Improvements in Fence Structures, of which the following is a specification.

This invention relates to fence structures, and has for an object to provide in a structure of this character novel and improved forms of posts for supporting the line wires and to provide one or more of such posts with wire tightening devices operable to receive the terminals of the line wires and to wind the terminals of the wires in a manner so that after the desired tension has been obtained they will be effectively held in their adjusted positions.

In the drawing, forming a portion of this specification and in which like numerals of reference indicate similar parts in the several views:—Figure 1 is a perspective view of a portion of a fence structure embodying my invention. Fig. 2 is a vertical section through one of the line posts. Fig. 3 is a horizontal section therethrough. Fig. 4 is an end view thereof.

The fence structure comprises the corner post 1, and the line posts 2 and 3. The corner post is preferably constructed from a single angle iron bar so as to present the angularly disposed vertical flanges 4 and 5 which are provided with passages 6 which are arranged in coincidence with each other so as to receive the line wires 7, which extend through receiving slots 8 in the line posts 2.

The post 3 is substantially of U-form in transverse section, being provided with the parallel spaced side flanges 14 and the curved connecting end portion 15 which latter has formed therein substantially superimposed relatively large and preferably oval or elliptical passages 16 which are arranged substantially in line with the passages 9 in the post 2. A winding shaft 17 is disposed immediately opposite each opening 16, and as shown, the ends of the shaft are journaled in the side flanges 14, one of the ends being extended outwardly beyond the flange 14 and formed to provide a substantially

squared portion 18 to receive any suitable well known form of socket or operating key, (not shown). The shafts 17 have fixed thereon vertically disposed ratchet wheels 19, the peripheral toothed surfaces thereof being designed for engagement with the spring pawls or locking dogs 20 on the end 15 of the post 3, the said dogs being adapted to hold the shafts 17 against retrograde movement. Each wheel 19 is provided on its opposite surfaces with horizontally disposed oppositely extending pins 21.

On reference to Figs. 1 and 2 of the drawing, it will be seen that the terminals of the line wires are extended into the post 3 and arranged respectively under and over the winding shafts 17 and correspondingly associated with the pins 21 so as to form in the terminal of each wire a confining or retaining hook 22. The terminals of the wires are so engaged with the pins 21 and with the shaft 17 that they may be securely wound spirally on the shafts so as to obtain the desired tension on the wires. The side portions 14 of the post 3 and the side portions 4 and 5 of the post 1 have their lower ends bifurcated, as at 24, so as to form a plurality of relatively sharp driving points 25. The post 2 has its side portion 8 formed at its lower end to provide a similar driving point 26.

I claim:

In a fence structure, a wire tightener supporting post of U-form in horizontal transverse section, providing spaced front and rear walls and a side wall, said side wall having a slot therein, a winding shaft journaled in said front and rear walls, a ratchet wheel mounted on said shaft and projecting partially through said slot, pins extending laterally from the sides of the ratchet wheel at diametrically opposite sides of and contiguous to said shaft, and a spring actuated pawl on the outer face of said wall engaging the teeth on the projecting portion of said ratchet wheel.

In testimony whereof I affix my signature in presence of two witnesses.

DAVID A. GOODRICH.
